UNITED STATES PATENT OFFICE

RALPH K. REYNOLDS, OF DANBURY, CONNECTICUT, ASSIGNOR TO MALLORY HAT COMPANY, OF DANBURY, CONNECTICUT, A CORPORATION OF CONNECTICUT

HAT CONSTRUCTION

Application filed August 24, 1927. Serial No. 215,023.

This invention relates to hat construction. One of the objects thereof is to provide a thoroughly practical hat of felt or other material having a brim embodying portions 5 having different colors or other contrasting or dissimilar appearance. Another object is to provide a practical felt hat the brim of which is provided with a welted or other edge portion contrasting with the remainder of the brim. Another object is to provide a construction of the above nature which is neat and attractive in appearance. Another object is to provide a construction of the above nature which is strong and rugged and which 10 will retain its shape when in use. Another object is to provide a practical art of making hats of the above general nature which may be carried on conveniently and rapidly and at low cost. Other objects will be in part 15 obvious or in part pointed out hereinafter.

The invention accordingly consists in the features of construction, combinations of elements, arrangements of parts and in the several steps and relation and order of each of 20 the same to one or more of the others all as will be illustratively described herein, and the scope of the application of which will be indicated in the following claims.

In the accompanying drawing in which are 25 shown one or more various possible embodiments of the structural features of the invention,

Figure 1 is a top plan view of a hat;

Figure 2 is a section, on a larger scale 30 through a portion of the crown of the hat and the brim, showing the brim at an intermediate stage during the process of its construction;

Figure 3 is a plan view of a ring or endless 35 strip of felt;

Figure 4 is a plan view of the parts shown in Figure 2;

Figure 5 is a section through the edge portion 40 of the brim of a completed hat showing one form of stitching;

Figure 6 is a section similar to that of Figure 5 showing the parts at an intermediate stage in the process;

Figure 7 is view similar to Figure 5 showing 45 another form of stitching;

Figure 8 is a view of one side of a brim portion showing a further form of stitching, and

Figure 9 is a view of the other side of the brim portion shown in Figure 8.

Similar reference characters refer to similar parts throughout the several views of the drawing.

Referring now to the drawing more in detail, there is shown in Figure 1 a hat comprising a crown 10 and a brim 11, the brim

having extending about the outer edge thereof a welt 12. The welt portion 12 of the brim is of a color different from that of the remainder of the hat, preferably contrasting therewith, as is indicated by the shading in Figure 1. The body of the hat shown herein, including the crown 10 and the main or body portion 11 of the brim, is of felt, preferably made in one integral piece in accordance with the usual methods of felt hat manufacture.

It is to be understood, however, that the details of construction of the crown and brim in their relation to each other are unimportant as relating to the broader features of this invention.

The differently colored outer portion 12 of the brim, preferably a welt, is also of felt and is a separate part, being secured to the main or body portion 11 of the brim as hereinafter described. A felt hat constructed in the manner shown in Figure 1, having an outer portion of the brim contrasting with the remainder thereof in color or other characteristics, such, for example, as the type of

finish, has a very desirable and attractive appearance.

In hat manufacturing plants there are ordinarily in the course of manufacture at the same time hats of various grades and colors and finishes. In accordance with certain features of my invention, briefly con-

sidered, I cut from the brim of a hat of one color a strip of felt which I use to make the edge portion, preferably a welt, upon a hat of a different color. For example, I may have two hats one of which is of a light color and the other of which is of a dark color. From the edge of the brim of the light colored hat, I cut a strip of felt for use upon the dark colored hat, and also, preferably, from the edge of the brim of the dark colored hat

I cut a strip of felt for use upon the light colored hat. In this manner I produce, without waste of material, a dark colored hat having a brim with a light colored edge portion, and a light colored hat having a brim with a dark colored edge portion. The process of building the brims in this manner is carried out after the hats have been "blocked" and brought to shape, the brims of the hats being at this stage flat, or substantially flat, and somewhat rough and uneven at their outer edges. When the hats are blocked and brought to shape, the brim is pulled out to the desired width, the crown being stretched over a block and ordinarily held in position thereon by a cord at the band as the pulling and shaping of the brim is done. In carrying out my process, when the two hats (for example, a light colored hat and a dark colored hat as mentioned above) are blocked and brought to shape, the brims are pulled out to a width which would be substantially sufficient to allow for the forming of a welt thereon in the usual and well-known manner. Thereupon, I cut from each of the brims, by cutting through the brim with a suitable tool, an endless ring-shaped piece of felt such as the ring 14 shown in Figure 3, the inside dimensions of these two rings being substantially identical. I then transfer the dark colored ring to the brim of the light colored hat and transfer the light colored ring to the brim of the dark colored hat, the inner edges of the rings abutting the outer edges of the respective brims and fitting snugly against the same since the brims were identically cut.

In Figure 2 there is shown the rim 11 from the outer edge of which has been cut a ring or endless strip of felt and, in the place of the part thus removed is positioned a ring 14 which has been cut from another hat of a different color. The inner edge of the ring or endless strip 14 abuts the outer edge of the brim 11 at 15. The parts having been thus positioned, the ring 14, in accordance with one method of construction, is sewed to the body 11 of the brim by means of stitching 16 which passes back and forth across the abutting edges 15, preferably in zigzag fashion as shown in Figure 4.

The parts having been thus secured together, the outer portion of the endless strip or ring 14 is thereupon curled over and pressed down against the adjacent brim surface as shown at 14^a in Figure 5, either against the upper surface of the brim or against the lower surface of the brim. This operation is accomplished by the use of curling and ironing tools or by a "plating machine", or by a combination of these various tools. In the curled over or folded over position of the strip 14 the part 14^a overlaps the joint 15. Thereupon, the part 14^a is sewed down against the parts therebeneath by means of stitching

passing through both the body 11 of the brim and the member 14. For example, two rows of ordinary through and through stitches may be employed, as shown at 17 and 18 in Figure 5, one row of stitching being on either side of the zigzag stitching 16. If desired, the stitching 16 may thereupon be removed or it may be left to strengthen the joint and, with the stitching 17 and 18, add to the ornamental appearance.

Instead of cutting off the rings or endless strips of felt 14 while the brims are flat, I may first form a welt by folding over the edge portion of the brim while it is still integral with the hat, and then cut off this folded portion to be used upon another hat. In Figure 6 the part 19 represents the brim of a hat whose edge portion 14 is to be cut off and transferred to the brim 11 of another hat. In accordance with the method mentioned just above I form upon the brim 19, by any of the well-known methods, a welt 14^a; thereupon, I cut from the brim 19 the edge portion 14 thereof, including the welt 14^a, by cutting around the brim at the line 20 beneath the welt 14^a. I thus remove from the brim 19 a longitudinally folded endless strip or ring of felt which I then transfer to the brim 11, as shown in Figure 7. The ring 14 with its welt 14^a is then sewed to the brim 11 by stitching such as 17 and 18 hereinbefore described.

Another form of stitching, and the form which I preferably employ, is that shown in Figures 8 and 9. This stitch consists of loops 21 passing through the welt 14^a and through the portion of the strip 14 therebeneath, and loops 22 extending at right angles to the loops 21 and passing across the joint 15. This form of stitching holds the abutting edges firmly together and firmly holds down the folded welt 14^a, and it also makes a very neat appearance on both sides of the brim. It is to be understood, also, that instead of stitching I may employ a suitable adhesive.

From the foregoing it will be seen that the construction provided herein is distinctly advantageous. A hat having a brim with a contrasting edge portion is provided in a thoroughly practical manner. The joint provided between the body of the brim and its attached edge portion is a combined butt and lap joint which is strong and dependable. The rounded edge of the folded strip of felt, facing outwardly, gives the edge of the brim a neat and finished appearance. The differently colored edge portion of the brim appears on both sides of the brim and, in combination with the stitching described, it makes a very attractive appearance both upon the upper brim and upon the under brim. The ring of felt, being endless, is free from joints which would detract from the finished appearance of the hat and would

weaken the brim. A brim constructed as described herein will dependably hold its shape in use. It will be understood that the welt may be provided either upon the upper surface of the brim or upon the under surface thereof. The process described is capable of being carried on conveniently and rapidly and without waste of material.

As many possible embodiments may be made of the mechanical features of the above 10 invention and as the art herein described might be varied in various parts all without departing from the scope of the invention, it is to be understood that all matter hereinabove set forth or shown in the accompanying 15 drawing is to be interpreted as illustrative and not in a limiting sense.

I claim:

1. A hat having a brim comprising an inner portion and an outer portion which are 20 secured together edge to edge to form a butt joint, the periphery of said outer portion being curled over to overlap said butt joint and secured to the underlying portions of said brim at both sides of said joint.
- 25 2. A hat having a brim comprising an inner portion and an outer portion which are secured together edge to edge, the periphery of said outer portion being curled over and overlapping the abutting edges of said two portions, and stitching passing through said curled over part and through both said inner portion and the part of said outer portion beneath said curled over part.
3. A felt hat having a brim comprising an 35 inner portion and an outer portion, said outer portion comprising an endless strip of felt the inner edge of which abuts the outer edge of said inner portion, the outer peripheral part of said strip being curled over and overlapping said abutting edges, and stitching securing said curled over part against the part therebeneath and passing from one side to the other of said butt joint.
4. A felt hat having a brim comprising an 45 inner portion and an outer portion which are secured together edge to edge to form a butt joint, the periphery of said outer portion being curled over to overlap said butt joint and secured to the underlying portions of said 50 brim, whereby said outer portion is secured to said inner portion by a combined lap and butt joint.
5. A felt hat having a brim comprising an inner portion and an outer portion, said outer 55 portion comprising an endless strip of felt the inner edge of which abuts the outer edge of said inner portion, the outer peripheral edge of said strip being curled to overlap said abutting edges, and the lap so formed being 60 fastened down to the underlying brim adjacent said abutting edges.

In testimony whereof, I have signed my name to this specification this 16th day of August, 1927.

RALPH K. REYNOLDS.
